DOORKNOB COVER

Justice Hall, Los Angeles County, Calif.
(12732 Darla Ave., Granada Hills, Calif. 91344)

Continuation of design application Ser. No. 87,748,
Oct. 22, 1965. This application Dec. 30, 1966, Ser.
No. 5,302

Term of patent 14 years

(Cl. D50—3)

The broken line showing of a doorknob is merely for illustrative purposes.

This is a continuation of design application Ser. No. D. 87,748 filed Oct. 22, 1965, and now abandoned.

I claim:

The ornamental design for a doorknob cover, substantially as shown and described.
